UNITED STATES PATENT OFFICE

2,483,318

OSCILLATOR

Benjamin J. Lazan, Greenwich, Conn.

Application July 13, 1945, Serial No. 604,781

5 Claims. (Cl. 74—61)

1

This invention relates generally to materials testing apparatus and more particularly to oscillators for producing a vibrating force which is normally used for loading structures or specimens under test.

It is an object of my invention to provide an oscillator having improved means for adjusting the degree of eccentricity of rotatable weights which produce the vibrating force, the magnitude of the force being in proportion to the degree of eccentricity. Another object in this respect is to provide an improved mechanism for adjusting the eccentric weights in such a manner that the adjusting forces are so related to each other as to insure not only ease in varying the eccentricity, but also in reducing to a minimum any wear and tear on the moving parts during operation.

A further object is to provide an improved oscillator in which the rotating eccentric weights and driving mechanism together with the adjusting elements are so arranged in a cooperative relation as to produce a highly compact device and yet have the parts easily assembled and accessible. In one particular aspect of my invention I accomplish the foregoing and certain other objects by mounting the major portion of the operating structure and adjusting mechanism about a common axis whereby the oscillator is of relatively small transverse dimensions and at the same time have the parts so related as to obtain a reasonable degree of accessibility without in any way sacrificing ease and precision of adjustment of the eccentric weights.

Other objects and advantages will be more apparent to those skilled in the art from the following description of the accompanying drawings in which:

Fig. 1 is a longitudinal vertical section taken substantially on the line 1—1 of Fig. 2;

Fig. 2 is a section taken on line 2—2 of Fig. 1, parts being shown in elevation for clarity;

Fig. 3 is an enlarged perspective of an eccentric weight and mechanism for adjusting the eccentricity, parts of which are broken away to show details of construction and the weight being shown in its lower position for purposes of clarity whereas the weights are shown in their upper position in Fig. 1;

Fig. 4 is a perspective of one of the combined drive sleeves and guides for the eccentric weights;

Fig. 5 is an elevational view of the shaft racks for adjusting a plurality of eccentric weights;

Fig. 6 is a side view of a modified arrangement

2

for supporting the eccentric weights by the adjusting racks;

Fig. 7 is a bottom plan view looking upwardly at the underside of Fig. 6; and

Fig. 8 is a transverse section taken on line 8—8 of Fig. 1.

In the specific embodiment of the invention disclosed herein for purposes of illustration, I provide a box-like casing 1 whose bottom side 2 is open to allow assembling of the rotatable force producing mechanism while a base plate 3 normally supports the casing. The force producing mechanism comprises a plurality of coaxial eccentric weights specifically shown as three in number 4, 5 and 6, respectively supported on drive sleeves 7, 8 and 9. These sleeves are journalled in ball bearings supported in the casing end wall 10 and also in transverse bearing supports 11 bolted to or otherwise formed as part 20 of the casing. Suitable downwardly removable bearing caps 12 are held on the bearing supports by bolts 13.

It will be understood that the weights 4 and 6 are driven together as a unit in one direction and the weight 5 is simultaneously driven at the same angular speed as weights 4 and 6 but in the opposite direction. The horizontal force components of the three weights are arranged to cancel out each other while the vertical components of all weights are additive both upwardly and downwardly. This is accomplished in the well-known manner of having the two sets of weights so angularly driven that during rotation the weights 4 and 6 will be on one horizontal side of the axis of rotation while the weight 5 is on the diametric opposite side. This leaves only vertical force components by reason of weights 4 and 6 moving toward a vertical plane from one side of the axis while weight 5 is moving toward the same point in the vertical plane from the opposite side of the axis, this movement taking place once at the lower side of the axis of rotation and again at the upper side thereof during each revolution thereby producing a vertical vibrating force.

In my improved arrangement I adjust the radial position of all weights in order to change the centrifugal force produced by the weights and accordingly vary the vibrating force capacity of the apparatus. To do this I have provided a plurality of coaxial sleeves 7, 8 and 9 of generally similar construction and hence the description of one will suffice for all except where otherwise noted. For convenience, the sleeve 7

is shown partially isolated in Fig. 4 and assembled in Fig. 1. It comprises cylindrical bearing portions 14 at each end with an intermediate square portion 15 in which a pair of vertical guideway slots 16 are formed of sufficient depth so as to intersect a substantial portion of a bore 17 extending through the entire sleeve length. Disposed in said bore is an axially shiftable hollow rack shaft 18 having rack teeth 19 and 20 cut on flatted surfaces on each side of the shaft. The arrangement of Fig. 4, in turn, supports the eccentric weight 4 in the manner shown in Fig. 3. The lengths of the individual sleeves are determined in accordance with the width of the different weights.

The weights may be formed in various manners one of which as shown in Fig. 3 comprises two main weight segments 23 and 24 held apart by a smaller central segment 25 all of which are bolted as by screws 26. The central segment 25 is provided with a pair of vertical slots one of which is shown at 27 for receiving a pair of transversely extending combined weight supporting and rack arms 28 and 29. These arms are rigidly connected together at their upper ends by a cross piece 30, Fig. 3, and bolts 31, while the lower end of the arms are firmly held in position by dowel pins such as 32, Fig. 5, extending through the arms 28 and 29 into the weight segments 23 and 24. The cap screws 26 also firmly clamp the lower ends of the rack arms between the central weight portion 25 to the outer portions 23 and 24. The rack teeth on arms 28 and 29 are inclined so as to mesh with the rack teeth 19 and 20, Figs. 3 and 4, of the axially shiftable rack shaft 18 whereby it is seen that upon axial movement of this shaft the inclined rack teeth will cause the rack arms and weights to be moved radially outward or inward, as the case may be, and thereby adjust the centrifugal force produced by the eccentric weights.

To drive the sleeves 7 and 9 together in the same direction while driving sleeve 8 in the opposite direction, I have provided as shown in Fig. 1 a shaft 35 which is keyed as at 36 to shaft 18. This shaft terminates at its right end in an enlarged cylindrical portion 37 having opposite flatted sides on which rack teeth 38 are formed to mesh with the rack arms of weight 6 in identically the same manner as that shown in Figs. 3 and 4 except that the rack teeth 38 are formed on a solid member such as 37 instead of a hollow rack shaft 18. The sleeves 7 and 8 are driven directly by bevel gears 39 and 40 while a bevel pinion 41 supported on a suitably journaled shaft 42 is driven from any suitable electric motor 43 or other power source. Hence, weight 5 is rotatably driven in one direction and weight 4 rotatably driven in the opposite direction, the driving force being transmitted, Fig. 4, through guideway 16 of sleeve 7 and thence to rack shaft 18 and key 36, Fig. 1, to shaft 35 which causes rotation thereof with consequent rotation of weight 6 through racks 38 and rack arms 28 and 29.

To radially adjust the weights, it will be first understood that a rack sleeve 45, Fig. 1, corresponding broadly to rack sleeve 18, is interposed between the latter sleeve and the left shoulder of enlarged shaft portion 37. Suitable thrust bearings 46 and 47 are disposed at each end of sleeve 45. Axial shifting of shaft 35 in either of opposite directions will cause the racks 38 and similar racks on sleeves 18 and 45 to adjust simultaneously the radial position of all weights.

To effect such axial adjustment of shaft 35 the enlarged portion 37 thereof is provided with a yoke 49 having a suitable thrust bearing 50. A plurality of symmetrically arranged screws 51 are threaded in yoke 49 and are journaled at their opposite ends in one of the journal supports 12 and in the end wall of casing 1. To rotate the screws 51 and thereby move yoke 49 and shaft 35 axially, each screw is provided with a wormwheel 52 commonly engaged by a worm 53. This worm may, if desired, be rotated in either of opposite directions by an electric motor 54 in accordance with the magnitude of vibrating force desired.

The weights may be additionally supported as shown in Fig. 6 by screws 56 extending from the outer weight segments 23 and 24 to an overhanging type of cross member 57 which takes the place of member 30 in Fig. 3. Suitable dowels 58 may be employed between member 57 and the weight supporting rack arms.

From the foregoing disclosure, it is seen that I have provided an oscillator having a high degree of transverse compactness, flexibility of operation and control, together with ruggedness as well as many other qualities and characteristics desirable in a device of this kind, the device being relatively narrow in its transverse dimensions by reason of having the oppositely rotating eccentric weights all mounted about a single common axis of rotation while other of the advantages arise from having the driving and adjusting forces largely self-contained within certain coating elements thereby avoiding the necessity of many complications heretofore present in oscillators of other types. It is to be noted that the weights are of different sizes, proportioned in accordance with the axial distance between each other so as to eliminate any torsional moments about a transverse plane. The difference in axial spacing of the weights is caused by the bevel gear drive interposed between two of the weights. To obtain axial compactness when the third weight is added but at the same time avoid torsional moments I arrange the masses as described.

It will of course be understood that various changes in details of construction and arrangement of parts may be made by those skilled in the art without departing from the spirit of the invention as set forth in the appended claims.

I claim:

1. An oscillator comprising, in combination, a plurality of eccentric weights, means for rotating said weights in opposite directions from each other about a common axis and in such angular relation to each other as to produce a resultant vibratory force in a predetermined direction, means for supporting said weights for movement radially of said common axis, and means movable axially along said common axis for radially adjusting said weights so as to vary the magnitude of the resultant force.

2. An oscillator comprising, in combination, a plurality of eccentric weights, means for rotating said weights in opposite directions from each other about a common axis and in such angular relation to each other as to produce a resultant vibratory force in a predetermined direction, and means movable along said common axis for adjusting said weights so as to vary the magnitude of the resultant force, said weights comprising at least two weights rotating together in one direction and spaced axially along the axis of rotation and another weight disposed between said axially

spaced weights and rotating in the opposite direction, the axially spaced weights being of different sizes and each of such weights being individually smaller than the intermediate weight, and said intermediate weight being axially spaced from one of the smaller weights a greater distance than from the other smaller weight, and driving mechanism for said weights being disposed within the space that has the greatest distance between the larger weight and one of the smaller weights.

3. An oscillator comprising, in combination, a plurality of weights certain of which rotate in one direction and others in an opposite direction along a common axis and in such angular relation to each other as to produce a resultant vibratory force in a desired direction, means for supporting said weights for movement radially of said axis and means movable along said common axis for radially adjusting at least one of said weights to vary the magnitude of the resultant vibratory force.

4. An oscillator comprising, in combination, a plurality of eccentric weights rotatable in directions opposite to each other about a common axis, individual sleeves arranged coaxially of each other and having transverse guideways intersecting their interiors, journals for said sleeves, transverse rack arms connected to said weights for supporting the same and radially slid able in said

10

15

20

guideways, and rack gears disposed within said sleeves for engagement with the rack arms and axially movable so as to effect radial adjustment of the rack arms and weights attached thereto.

5. An oscillator comprising, in combination, a plurality of eccentric weights rotatable in directions opposite to each other about a common axis, individual sleeves arranged coaxially of each other and having transverse guideways intersecting their interiors, journals for said sleeves, transverse rack arms connected to said weights for supporting the same and radially slid able in said guideways, rack gears disposed within said sleeves for engagement with the rack arms and axially movable so as to effect radial adjustment of the rack arms and weights attached thereto, and means for rotatably driving said axially movable racks whereby rotation is imparted from at least one of the axially movable racks through its co-operating rack to the weight attached thereto.
